UNITED STATES PATENT OFFICE.

FRANK H. STETSON, OF METHUEN, MASSACHUSETTS, ASSIGNOR TO U. S. BOBBIN & SHUTTLE CO., OF PROVIDENCE, RHODE ISLAND, A CORPORATION OF RHODE ISLAND.

SHUTTLE-BLOCK PIN.

Application filed May 25, 1921. Serial No. 472,363.

To all whom it may concern:

Be it known that I, FRANK H. STETSON, a citizen of the United States, residing at Methuen, in the county of Essex and State of Massachusetts, have invented certain new and useful Improvements in Shuttle-Block Pins, of which the following is a specification.

This invention relates to shuttles for looms, and is peculiarly adapted for such shuttles as are used in weaving worsted yarn or thread, which has a very strong tendency to cut metal.

I am aware that pins of metal, preferably steel, have been used in connection with threading blocks of shuttles for the yarn to turn around at right angles so that the thread, which starts to unwind and play out along the longitudinal axis of the shuttle, can pass out at right angles thereto through a suitable shuttle eye.

I am also aware that a metal roller has been substituted for this pin, and I am further aware that a roller of porcelain or other wear resisting material has also been tried in this position but set at an angle.

Where worsted yarn or thread is used, it will cut a steel pin or steel roller, and where a porcelain roller is used, the yarn will either catch between the ends of the roller and its supports or must be protected by means which are generally inadequate from the tendency of the roller as it turns to catch the yarn in such places.

My invention preferably comprises a porcelain tube or other suitable member of wear resisting material supported from the top by means of a metal pin which is passed through it and thence into the under part of the top of a threading block, such wear resisting member being fixed to such a pin.

By so locating and fastening my wearing member, which is preferably a porcelain or glass tube, with one end fixed and the other end free, a certain amount of vibration is allowed which helps to prevent cracking and breaking. Besides this, there is no loose nor rolling part to wear unevenly, to rattle or break.

In the drawings, Fig. 1 is a plan view of a shuttle with the shuttle block having my preferred form of pin in position.

Fig. 2 is a side elevation of a shuttle block

partly broken away with my preferred form of pin in position.

Fig. 3 is a sectional elevation on the line 3—3 of Fig. 1 looking from the direction of the arrow, the wood being shown in section and the metal not in section showing my preferred form of shuttle block with my preferred form of pin in position in a shuttle.

Fig. 4 is an elevation from the front, and Fig. 5 is an elevation from the side of a shuttle block of slightly modified form with my preferred form of pin in position.

Fig. 6 is a sectional elevation showing the adjoining parts of a pin and shuttle block such as shown in Figs. 4 and 5.

Fig. 7 is a sectional elevation of a slight modification of the relation between my pin and shuttle block.

Figs. 8, 9 and 10 are sectional elevations of variations of my wearing member.

Fig. 11 is a vertical sectional elevation as from the right of a shuttle, or as from the direction of the arrow on line 11—11 of Fig. 1, showing the application of my compound pin to a shuttle in a different manner.

Figs. 12 and 13 show in sectional elevation other variations in the application of my compound pin.

Fig. 14 is a vertical sectional elevation of a compound pin of my preferred construction.

In the drawings, A represents a shuttle having the usual delivery eye 11 in the wood and suitable thread guiding recesses, indicated by 12, connecting therewith. 13 represents a block recess in which is located a threading block N, the top of which is flush with the top 10 of the shuttle. This is shown as having the usual projection 30 and as having the usual fastening hole 28 through which passes horizontally a screw 95 or bolt 14 to hold the block in position.

This threading block has a threading chamber C, and in a preferred construction, shown in Figs. 2 and 3, has at the back a locking guide 27 and is formed with a guide plate 20 which extends into the threading chamber and at the back terminates in a guide hook 22 which extends down below or overlaps the locking guide 27. Preferably it also has at the front a thread trapping rim 21, and it has the usual guide horn 23.

which guides the yarn down into the threading chamber.

A little behind and adjacent to horn 23 is a boss 19 in which is a wearing member recess 25 from which extends upward through the top of the threading block a pin hole 26.

A pin 36 having a head 38 extends up through pin hole 26, being driven thereinto or soldered therein by solder 37 so that it is fixed in position. It extends downward in a direction substantially perpendicular to the plane of the movement of the thread, and carries a wearing member of wear resisting material, such as porcelain or glass, preferably of tubular form shown at B. This member is fixed to pin 36 by means of cement, or it may be fixed thereon or otherwise fastened so that it will not revolve.

The upper end of this member B extends into the recess 25, while its lower end, proximate pin head 38, is free to vibrate.

Preferably, a friction member E is passed through a horizontal transverse hole 29 which is proximate and just behind and below wearing member B at the front and bottom of threading chamber C.

Extending backward from horn 23 is preferably a wing or web 24 in a position midway in the height of member B and slightly above the top of friction member E.

The tendency of locking guide 27, friction E, and wing 24, is to keep the thread M in the position shown, and prevent it from running off the ends, top, or bottom of the wearing member.

Preferably also, shuttle eye 11 and other parts are so placed that the normal tendency of the thread is to run about the middle part of tube B.

In Figs. 4 and 5, I show a threading block H similar in most respects to that shown at N but without the overlap 27, and instead of a protecting wing, such as 24, running directly back from horn 23, I show a diagonal protecting wing 44 which extends down below the top of tube B. This can be used in place of wing 24 or in addition thereto and serves to prevent the thread M from getting caught between the top of B and the bottom of 19, especially where, as shown in Fig. 6, there is no recess for the wear resisting member such as 25.

In Fig. 7, I show a boss 19 with a recess 50 for tube B of slightly different form from that shown at 25, the pin 36 and other parts of the block K being the same as N.

As shown in Fig. 8, I may use a pin 60 with a flat head 61 which sets into a recess 63 in tube 62 whereby the head does not project at all.

As shown in Fig. 9, I can use an hour-glass shaped wear resisting member 70 con-

stricted at 71 and carried by a pin 36 with a head 38, or I can use a block 80 of wear resisting material having a groove 81 and through which passes the pin 36 with head 38, as shown in Fig. 10.

As shown in Fig. 11, I may use a porcelain tube 90 held in position by the headed pin 86 driven into the hole 91 in the shuttle block 92 directly under the hole 93 in the eye block E, the hole 93 being large enough to form a clearance around the porcelain tube 90. In this method of construction, the eye block E may be removed separately from the pin.

Fig. 12 shows a construction similar to Figs. 8, 9 and 10, except that the pin 96 is headless and the porcelain tube 90 rests firmly between the metal eye block E and the wood 92 of the shuttle.

Fig. 13 shows a similar construction to Figs. 11 and 12 with the head left off the pin 97 and a web 94 extending outside the tube 90. The tube 90 is in close contact between block E and the wood 92 of the shuttle.

In Fig. 14, I show in section a compound pin of my construction removed entirely from the shuttle. In this view B represents the tube of porcelain or glass, 36 the headed metal pin and 39 the cement by which they are fixed together.

I claim:

1. In a shuttle for looms, having a delivery eye, suitable thread guiding recesses in the wood connecting therewith and a block recess; the combination of a threading block fixed in the block recess having a threading chamber, which has at the back a locking guide, a guide plate which extends into the threading chamber and at the back terminates in a guide hook which overlaps the locking guide; a horn near its front, a wearing member recess and a pin hole which extends therefrom through the top of the threading block, both behind and proximate said horn, together with a protecting wing adjoining said recess; with a pin fixed in said pin hole and extending down therefrom in a direction substantially perpendicular to the plane of the movement of the thread and terminating in a head; a wearing member of wear resisting material of tubular form carried by and fixed on said pin which enters said wearing member recess in the threading block; and is free at its lower end to vibrate; and a friction member proximate the wearing member located at the front and bottom of the threading chamber.

2. In a shuttle for looms having a delivery eye, suitable thread guiding recesses in the wood connecting therewith and a block recess; the combination of a threading block fixed in the block recess having a horn near its front, a threading chamber,

and a pin hole which extends therefrom through the top of the threading block to a point behind the horn; with a pin fixed in said pin hole and extending down therefrom in a direction substantially perpendicular to the plane of the movement of the thread and terminating in a head; a wearing member of wear resisting material carried by and fixed on said pin; and a friction member proximate the wearing member located at the front and bottom of the threading chamber.

5. In a shuttle for looms having a de-

livery eye, suitable thread guiding recesses in the wood connecting therewith and a 15 thread-block recess; the combination of a threading block fixed in the block recess having a horn near its front, a threading chamber, and a pin hole which extends therefrom through the top of the threading block to 20 a point behind the horn; with a pin fixed in said pin hole and extending down therefrom; and a wearing member of wear resisting material carried by and fixed on said pin.

FRANK H. STETSON.
